Fig. 3

Fig. 4

Fig. 5

Fig. 6

Fig. 7

FIG. 1 is a front perspective view of a cooking range, showing our new design;

FIG. 2 is a front perspective view thereof with the burner top exposed;

FIG. 3 is a front perspective view thereof with the burner top shown in extended position;

FIG. 4 is a front elevational view thereof;

FIG. 5 is a side elevational view thereof;

FIG. 6 is a side elevational view thereof with the burner top exposed;

FIG. 7 is a side elevational view thereof with the burner top shown in extended position;

FIG. 8 is a front elevational view of a modified form of the design shown in FIGS. 1-7;

FIG. 9 is a front perspective view thereof with the burner top exposed;

FIG. 10 is a front perspective view thereof with the burner top shown in extended position.

The broken lines indicative of the lower portion of

the range have been omitted in FIGS. 2 to 10 for convenience of illustration.

The top and rear not shown are plain and the opposite side not shown is substantially like the side shown.

The dominant features of our design reside in the portions shown in full lines.

We claim:

The ornamental design for a cooking range, as shown and described.
